US00D922962S

(12) **United States Design Patent** (10) Patent No.: **US D922,962 S**
Morita et al. (45) Date of Patent: ** Jun. 22, 2021

(54) **PUSH SWITCH**

(71) Applicant: **OMRON Corporation**, Kyoto (JP)

(72) Inventors: **Kazuaki Morita**, Izumo (JP); **Yusuke Komoguchi**, Okayama (JP); **Tadahiko Ogawa**, Moriyama (JP); **Masami Nishida**, Osaka (JP)

(73) Assignee: **OMRON Corporation**, Kyoto (JP)

(**) Term: **15 Years**

(21) Appl. No.: **29/761,575**

(22) Filed: **Dec. 10, 2020**

(57) **CLAIM**

The ornamental design for a push switch, as shown and described.

DESCRIPTION

FIG. 1 is a top, front, and right side perspective view of a push switch showing our new design;

FIG. 2 is a front view thereof;

FIG. 3 is a left side view thereof;

FIG. 4 is a right side view thereof; and,

FIG. 5 is a bottom view thereof.

The dashed broken lines illustrate portions of the push switch that form no part of the claimed design. The dot-dashed broken lines depict the bounds of the claim and form no part thereof. The unshaded surfaces form no part of the claimed design.

1 Claim, 5 Drawing Sheets
